UNITED STATES PATENT OFFICE.

CHARLES E. REDDIG, OF RICHMOND HILL, NEW YORK, ASSIGNOR TO WESTERN ELECTRIC COMPANY, INCORPORATED, OF NEW YORK, N. Y., A CORPORATION OF NEW YORK.

VAPORIZER.

Application filed August 22, 1919. Serial No. 319,055.

To all whom it may concern:

Be it known that I, CHARLES E. REDDIG, a citizen of the United States, residing at Richmond Hill, in the county of Queens,

5 State of New York, have invented certain new and useful Improvements in Vaporizers, of which the following is a full, clear, concise, and exact description.

This invention relates to vaporizers for 10 use in connection with internal combustion engines and more particularly to a vaporizer especially adapted for producing an explosive mixture at the time of starting such an engine.

15 In various types of internal combustion engines trouble is experienced at starting due to the fact that the fuel often cannot be satisfactorily vaporized without applying heat, and furthermore, if the engine is cold 20 the vapors quickly condense on the walls of the cylinder and other metal parts until such parts are heated as the result of the operation of the engine. This is particularly true in the case of engines which employ kerosene as the fuel oil, since kerosene is much less volatile than gasoline which is 25 more commonly used. In connection with engines employing kerosene, it has been the usual practice to provide arrangements for 30 starting the engine with gasoline and, after the parts have become heated in operation, to discontinue the supply of gasoline and provide in its place a supply of kerosene for 35 maintaining the engine in operation. Such an arrangement, however, is unsatisfactory in that it necessitates providing storage means for two different kinds of fuel and also a special arrangement for injecting the 40 different vapors into the cylinder of the engine.

It is therefore an object of the present invention to provide means for quickly and thoroughly vaporizing a combustible liquid used as fuel in an internal combustion engine.

45 It is another object of the invention to provide a vaporizer in which the liquid fuel is first heated and then after it is vaporized and mixed with air the mixture is further 50 heated before it passes into the combustion chamber of the engine.

A still further object of the invention is

to provide a vaporizer accomplishing the above objects which will be simple of construction, cheap to manufacture, and efficient in operation.

To accomplish these objects and in accordance with a feature of the invention, there is provided a vaporizer equipped with electrically heated means for quickly and efficiently heating and vaporizing the liquid fuel as it is received from the storage tank.

In accordance with another feature of the invention, means are provided for mixing the heated vapor with the proper amount of air to provide the desired explosive mixture and this mixture is further heated before it is allowed to pass into the combustion chamber of the engine.

These and other features of the invention 70 may be more clearly understood by reference to the accompanying drawing in which Fig. 1 is a vertical cross-section partially in elevation showing a vaporizer embodying the features of this invention; Fig. 2 is a 75 sectional view taken in a plane perpendicular to the plane of Fig. 1; Fig. 3 is a top view of the vaporizer with the upper casting and heating element removed; and Fig. 4 is a vertical cross-sectional view showing 80 more clearly the construction of the heating element as disclosed in Figs. 1 and 2.

Referring now to the drawings, there is provided a metal housing including an upper member 6 and a lower member 7. An 85 intermediate member 8 preferably of brass is positioned between the members 6 and 7 and the parts are securely held in place by means of the screws 9 which pass through suitable openings in the members 90 6 and 8 and engage the threads of corresponding openings in member 7. The intermediate member 8 comprises a circular plate portion 10 in which are provided a pair of semi-circular openings 11-11. The 95 center portion of this member includes a hollow stem 12 which extends up into the tubular portion 13 of member 6. Radial ribs 14 and 15 disposed 180° apart are provided in member 8. Rib 15 is provided with a longitudinal perforation 16 which intersects the perforation 17 in stem 12 and also intersects a vertical perforation 18 which extends to the tube 19 leading to the source.

of fuel supply. A needle valve 20 is provided with a threaded portion adapted to engage similar threads in rib 15 and its tapered portion engages a valve seat located in perforation 16 as shown. A suitable packing gland 21 is provided for needle valve 20 to prevent leakage of fuel. The rib 14 is provided with a similar needle valve 23 which is provided with a packing gland 24 for preventing leakage of fuel. This valve extends in a horizontal perforation 25 in rib 14 and opening directly into the tube 19 which extends to the source of fuel supply. The perforation 25 is intersected by a perforation 26 centrally located in the member 8 and extending downward. A bushing 27 is provided in the tubular portion 13, tapered as shown to provide a restricted opening in line with the upper portion of stem 12. Located between this bushing and the flange portion 28, which is adapted to be secured directly to the intake manifold of the engine, is a butterfly valve 29 which is attached to a shaft 30 and regulated by movement of the crank 31. The member 6 is provided with a plurality of ribs 32, 33, 34, and 35 which are in alignment with similar ribs 36, 37, 38, and 39 extending upwardly from member 8. The lower member 7 is also provided with similar ribs 40, 41, 42, and 43 which are in alignment with similar ribs extending downwardly from intermediate member 8. These rib members are provided for the purpose of clamping in place an upper heating element 45 and a lower heating element 46. These disc-shaped heating elements may be of any desired construction but, as shown, consist of a sheet of mica 48 about which is wound a coil of resistance wire 49 which passes over and under the sheet, the wire having sufficient rigidity to remain in the position in which it is shaped. Insulating sheets 50—50 of mica or similar material are provided to protect the outer side of the winding and the element is enclosed in a casing 51 which is preferably of copper or other good heat conducting material. The ends of each winding 49 are brought to terminal connectors 52—52 located in a block 53 of insulating material such as hard rubber which is held in place on the intermediate member 8 by means of the screws 54—54. The heating coils 45 and 46 may be connected either in multiple or in series as desired. The upper heating element is provided with a circular opening 55 through which extends the tube 12. The lower heating element 46 is provided at its center with a conical member 56 which is preferably of copper because of its good heat conducting properties. The lower member 7 is provided with an opening 58 which is controlled by means of a butterfly valve 59

secured to shaft 60, which controls the opening of the passageway leading to the interior of the device.

The operation of this device at the time of starting is as follows:

A source of electric energy is connected to the terminals 52—52 and causes current to flow through the heating elements 45 and 46. Needle valve 23 is then opened, allowing the liquid fuel to flow from the tube 19 leading to the source of supply through the perforations 25 and 26. As the fuel leaves perforation 26 it drops upon the heated member 56 which, because of its conical shape, causes the fuel to be spread out over a comparatively large surface. Because of the heat of this member, the liquid fuel is quickly and thoroughly vaporized and as the engine is turned over, the suction caused by the movement of the piston draws this vapor upward through the openings 11—11, thence outwardly past the lower side of member 45, through the circumferential opening 58, thence along the upper portion of heating element 45, through the bushing 27 and past the valve 29 to the intake manifold. It will be seen that this path for the vapor causes it to be thoroughly heated at the time it reaches the engine. After the engine has become heated due to its operation, the needle valve 20 is opened, causing liquid fuel to flow through the openings 16 and 17, and at the opening of tube 12 it is mixed with the heated air forming an explosive vapor which then passes on into the intake manifold. The needle valve 23 is then closed and the circuit for the heater coils 45 and 46 opened, allowing the vaporizer to function in the ordinary manner. The valve 59 is provided to regulate the amount of air to be mixed with the fuel and, preferably at the time of starting, this valve is completely closed in order to provide a very rich mixture at this time. The valve 29 is provided for the purpose of regulating the amount of mixture to be supplied to the engine.

If desired, the needle valve 20 may be left open during the entire period of operation, since means, such for example as a vacuum feed float chamber of usual construction (not shown), may be provided for maintaining the level of the liquid slightly below that of the upper portion of stem 12. Under such a condition, upon starting it is only necessary to open the needle valve 23 and close the circuit through the heating coils and then when the parts have become heated, the needle valve 23 may be closed, the circuit for the heating circuit opened, and the device will then function in the regular manner. While such a device is particularly advantageous for use in connection with engines operated upon the less volatile fuels,

such as kerosene, it is also of considerable advantage in connection with engines employing volatile fuels, such as gasoline, in case such engines are exposed to low temperatures. If desired, the circuit from the heating coils may be arranged to be opened and closed automatically upon operation of the heating valve 23, and also if desired, the circuit through the heating coils may be kept closed to assist in the vaporization of the fuel during the complete operation of the engine.

What is claimed is:

1. A vaporizer for internal combustion engines, comprising a mixing chamber, air and fuel inlet passages and a mixture outlet passage communicating therewith, and electrically heated superimposed plates arranged to heat and baffle the air and mixture passing through said chamber.
2. A vaporizer for internal combustion engines comprising a chamber, an air inlet passage and a mixture outlet passage communicating therewith, two superimposed electrically heated elements disposed within said chamber to baffle the air and mixture passing therethrough, and independent fuel inlets adapted to feed fuel above each of said heated elements.
3. A vaporizer for internal combustion engines comprising a mixing chamber, an air inlet passage and a mixture outlet passage communicating therewith, electrically heated elements arranged to baffle the air and mixture passing through said chamber, fuel inlets arranged to feed fuel above each of said heated elements, and valves for controlling the feeding of fuel to said fuel inlets.
4. A vaporizer for internal combustion engines comprising a chamber, an air inlet

passage and an explosive mixture outlet passage communicating therewith, two superimposed heating elements disposed within said chamber to baffle the air and explosive mixture passed therethrough, a fuel inlet arranged to feed fuel onto the upper surface of the lowermost heating element, a second fuel inlet adapted to feed fuel at a point above the top surface of the uppermost heating element, and valves for independently controlling the feeding of fuel to the said inlets.

5. A vaporizer for internal combustion engines comprising a chamber, an air inlet passage and an explosive mixture outlet passage communicating therewith, a valve in each passage for controlling the passage of air and explosive mixture therethrough, two superimposed heating elements disposed within said chamber to baffle the air and the explosive mixture passed therethrough, a fuel inlet arranged to feed fuel above the upper surface of the lowermost heating element, a second fuel inlet adapted to feed fuel above the top surface of the uppermost heating element, and valves for independently controlling the feeding of fuel to the said inlets.

6. A vaporizer for internal combustion engines comprising a chamber, an air inlet passage and an explosive mixture outlet passage communicating therewith, two heating elements disposed within said chamber, a fuel inlet arranged above each of the said heating elements, and valves for independently controlling the feeding of fuel to the said inlets.

In witness whereof, I hereunto subscribe my name this 20th day of August, A. D., 1919.

CHARLES E. REDDIG.
